UNITED STATES PATENT OFFICE.

ERWIN L. WILKE, OF HAMMOND, INDIANA, ASSIGNOR TO METALS REFINING COMPANY, OF HAMMOND, INDIANA, A CORPORATION OF INDIANA.

CASTING MACHINE.

Application filed September 6, 1921. Serial No. 498,814.

To all whom it may concern:

Be it known that I, ERWIN L. WILKE, a citizen of the United States, residing at Hammond, in the county of Lake and State 5 of Indiana, have invented new and useful Improvements in Casting Machines, of which the following is a specification.

This invention relates to casting machines and more particularly to casting machines 10 for casting storage battery grids.

One object of the invention is to fill the molds by submerging the same, while closed, in the molten metal and allowing the cavities to fill, the air escaping as the cavities fill, thus producing cast products conforming 15 minutely to the contour of the cavities, no matter how complex, by avoiding trapping air and producing air pockets in the products.

Another object of the invention is to make 20 the machine automatic in its operation so that filling the molds, ejecting the cast product therefrom, and repeating the operations may be done without the attendance 25 of an operator after the machine has been set in motion.

A still further object is to permit the casting of a plurality of products all at one time and thus increase the production of the 30 machine.

The invention consists further in the matters hereinafter described and more particularly set forth in the appended claims.

In the accompanying drawings—

Fig. 1 is a top plan view of a casting machine constructed in accordance with my invention;

Fig. 2 is a vertical sectional view taken on line 2—2 of Fig. 1 and showing a detail of construction;

Fig. 3 is an enlarged top plan view of said machine, the driving mechanism at opposite ends of the machine being omitted for the purposes of illustration.

Fig. 4 is a transverse vertical sectional view taken on line 4—4 of Fig. 3;

Fig. 5 is a longitudinal vertical sectional view taken on line 5—5 of Fig. 3;

Fig. 6 is an end elevational view of said machine;

Fig. 7 is a side view with parts in section of one of the mold members;

Fig. 8 is a vertical sectional view taken through said mold member on line 8—8 of Fig. 7;

Fig. 9 is a perspective view of a battery grid cast by the machine; and

Fig. 10 is a side view of the switch actuating mechanism to be hereinafter described in detail.

The casting machine of my invention, as shown in the drawings, comprises a base 1, on which is mounted an upwardly opening, trough shaped member 2 arranged to extend across the machine and located between the ends thereof. Suspended in the trough 2 is a crucible or melting pot 3 adapted to contain the molten metal from which the products cast by the machine are made, the source of heat for maintaining the metal in the pot 3 in molten condition being contained within the trough member 2.

Mounted on the base 1 are a plurality of upright standards 4, 4, one at each corner of the base. This provides a pair of standards 75 at each side of the machine and on opposite sides of the pot 3, as shown in Figs. 1, 3, and 5. Extending between the standards 4, 4, at each side of the machine, is a rail or track-way 5 secured at its ends to sleeves 6, 80 6 slidably mounted on the standards. Extending across the machine above the pot 3 and between the rails 5, 5 is a carriage 7 in the form of a flat plate or table. This is supported by the rails 5, 5 and has a connection therewith permitting the carriage to be moved or slid endwise of said rails, the carriage, in the instance shown, having depending side flanges 8, 8 in grooves in the rails 5, as illustrated in Fig. 4.

Depending from the under side of the carriage 7 are a plurality of molds 9, 10, arranged in two lateral rows, with three molds 9 in one row and the three molds 10 in the other row, in the particular machine illustrated. The molds are all made alike and operate in the same manner as each other. Each mold, as shown in Figs. 7 and 8, comprise a stationary mold member 11 and a movable mold member 12, these being connected together adjacent their upper ends by a hinge pintle 13. To normally maintain the mold members closed, I provide a spring 14, as shown in Fig. 7. As illustrated in

Figs. 7 and 8, the mold members of each mold are provided with registering mold cavities 15, 15, arranged side by side and having shapes and contours to cast two battery grids, such as 16 in Fig. 9. To eject the grids from the mold after being cast and when the mold is open, I provide each of the two mold members of each mold with spring pressed ejector pins 17. These are arranged 10 at one of the corners of each of the mold cavities and are held retracted from the cavities during the casting operation by the pins contacting with each other when the mold is closed. The contacting ends of the 15 pins are reduced or cut away sufficiently to form shoulders which bear against the grids and eject them from the mold when the mold members are swung apart. These pins 17 are provided on each of the mold members so that, should the cast grid stick or 20 adhere to either of the mold members when swung apart, the ejector pins of the mold member to which the casting adheres will eject the cast product therefrom.

25 Journalled in the base 1 is a shaft 18. This extends lengthwise of the machine and under the heat containing trough or chamber 2. Fixed on this shaft are two cam members 19, 19 having the same general contour as shown in Figs. 4 and 6. Extending between and secured to the sleeves 6, 6, at each end of the machine, is a frame 20 provided at its lower end with a roller 21 bearing on the periphery of the associated cam 30 19, as best illustrated in Figs. 4 and 6. For rotating the shaft 18, I provide an electric or other motor 22 at one end of the machine, as shown in Figs. 1 and 6. This motor is mounted on a suitable support (not shown) 35 and has driven by its armature shaft a worm 23 in mesh with a worm gear 24 keyed or otherwise fixed to the shaft 18. This gearing is located in a protective housing 25, as shown in the drawings. When the shaft 18 is rotated, the cams 19, 19 thereon act to move the carriage 7 up and down for carrying the molds 9 and 10 into and out of the molten metal in the crucible or pot 3, the frames 20 being raised and lowered and the 40 sleeves 6, 6 sliding vertically on the standards 4.

45 For reciprocating the carriage 7 horizontally, for carrying the molds 9 and 10 alternately into and out of position over the crucible 3, I provide, at the other end of the machine, an electric or other motor 26, also mounted on a suitable support (not shown). On the armature shaft of this motor is a gear pinion 27 in mesh with a gear wheel 28 50 on a shaft 29 journalled in a gear casing or housing 30. On the shaft 29 is a worm 31 in mesh with a worm gear 32 fixed on a shaft 33 journalled in said casing and projecting outward therefrom at one side of the same, 55 as shown in Fig. 1. On the shaft 33 is a

gear pinion 34 in mesh with a gear wheel 35 fixed to one end of a crank shaft 36. The crank pin 37 of this shaft is slidably retained in a Dutch yoke 38 extending to and connected with the carriage 7 at one end thereof, as shown in Figs. 1 and 2.

The machine shown and described operates as follows. The metal from which the grids 16 are to be cast is placed in the crucible or pot 3 and brought to molten condition by applying heat to the under side of said pot. At this time the machine is at rest and both cams 19, 19 are in the position shown in Fig. 6. This holds the carriage 7 raised with both rows of molds 9 and 10 out of and above the pot 3, with the set of molds 9 directly above the pot and the set 10 over and above one of the discharging spaces at one side of the pot 3. The motor 22 is started and rotates the shaft 18 in a direction to cause the cams 19 to lower the carriage 7 and cause the molds 9 and 10 to descend. This brings the rows of molds 9 down into the molten metal in the pot 3, the mold cavities filling by gravity 90 as soon as the molds are submerged sufficiently to carry their inlet openings 15^a below the level of said metal. (See Fig. 8.) As the cavities fill, air is expelled therefrom through vent passages 15^b, one for each cavity and opening into the atmosphere above the level of the metal in the crucible 3. This manner of filling the mold, by submerging the mold with the mold members closed and allowing the cavities to fill by 95 gravity, the air being free to pass out of the cavities as the level of the metal rises therein, prevents the trapping of air in the cavity and thus produces a cast product perfect in outline and detail and conforming exactly 100 to the contour and shape of the cavity without imperfections being formed therein, as encountered by the method heretofore employed. My improved method is highly advantageous in casting battery grids because 105 the many cross bars of the product are perfectly formed, united one with the other and free from breaks and other faults so numerous as heretofore. This makes the metal of a substantially uniform thickness 110 throughout and all parts properly united, thus making the grid better able to withstand the duty imposed upon it and making it last longer and more efficient.

115 As the carriage 7 is lowered, the other set 120 of molds 10 descend into one of the spaces at the sides of the pot 3, as shown in Fig. 5. The trough 2 has at each side thereof a number of downwardly inclined rails, 39 on one side for the molds 10 and 42 on the opposite side for the molds 9, there being a rail for each mold in the row. The movable member 12 of each mold carries at its lower end a roller, 40 on the molds 10 and 40^a 125 on the molds 9, to engage at the proper time 130

the associated inclined rail 39 or 42 as the carriage 7 descends to open the molds by swinging the movable mold members 12 outward from the stationary ones 11. The pins 5 17 eject the cast grid from the open molds, and the cast grids as discharged may be caught in a car 41 below the row of discharging molds.

After the molds 9 have filled, a continued 10 rotation of the shaft 18 causes the cams 19 to raise the carriage 7 and carry the mold members 9 out of the pot 3, at the same time raising the other set of molds 10, these closing as the rollers 40 pass off the upper 15 ends of the rails 39. As soon as the molds 9 and 10 have cleared the top of the crucible 3, the carriage 7 has reached the limit of its upward movement, and an electric switch mechanism, to be hereinafter described, 20 is operated to turn off the current to the motor 22 and stop the same. Immediately after, current to the other motor 26 is turned on through said switch mechanism and the carriage 7 moved on the rails 25 5 horizontally in a direction to shift the loaded molds 9 from over the crucible 3 to a position over the discharging space at the adjacent side of the trough 2. At the same time the empty molds 10 are shifted into 30 position over and above the crucible 3. This motion is caused through the rotation of the crank shaft 36 and the reciprocation of the yoke 38. When the two rows of molds are thus positioned, the current to the motor 26 35 is turned off automatically, through said switch mechanism, and also through the latter the current is again turned on to the motor 22. As the latter is operated, the carriage 7 is again lowered and forces the 40 now empty molds 10 into the batch of molten metal in the pot 3 for filling said molds by gravity in the same manner as heretofore described. While the molds 10 are being lowered for filling, the others 9 45 are opened for discharging by their rollers 40^a engaging the downwardly inclined rails 42. After the molds 10 have been filled and the molds 9 have been emptied, the carriage 7 is again raised and, when reaching the 50 limit of its upward movement, operates the switch mechanism to turn off current to the motor 22 and turn on current to the motor 26. This operates through the yoke 38 to draw the carriage 7 back into position with 55 the loaded molds 10 over their discharging space and the empty molds 9 over the crucible 3. When the parts reach this position, the motor 26 is stopped and the motor 22 again started to lower the molds, the empty 60 ones 9, into the crucible 3 for filling and the loaded ones against the rails 39 for discharging. After these operations are completed, the table or carriage 7 is again raised and the cycle of movements repeated.

65 The switch mechanism mentioned is con-

structed and operates as follows. At one end of the machine is a controller switch 43 of any preferred construction and in circuit with both motors 22 and 26. The switch 43 is of the rotary type and includes a shaft 44 extending across the machine and above the path of vertical movement of the carriage 7. This shaft 44 is journaled in brackets 45, 45 supported from the adjacent standards 4, 4. Fixed to the shaft adjacent 70 one end are two star wheels 46, 47, the former operated through the vertical movement of the carriage 7 and the latter through the horizontal movement of the same. For the wheel 46, the carriage 7 is provided with 75 an upright bar 48 (Figs. 4 and 10) having a pivoted trip 49 at its upper end and in the path of the spokes of the star wheel 46. As the carriage 7 descends, the trip 49 trips over the interposed spoke of the wheel 46 80 and does not turn the same, as the motor 22 is kept in operation during the descent and rise of the carriage 7. As the carriage is raised, however, the trip 49 contacts with the spoke in its path and turns the wheel 46 85 to cut off the current to the motor 22 as soon as the carriage reaches the limit of its upward movement. Through the wheel 46, the current is also turned on to the motor 26, as soon as the motor 22 is stopped, to 90 draw the carriage horizontally for changing the position of the rows of molds 9 and 10.

At one end of the carriage is an arm 50 in the same horizontal plane of the carriage and projecting therefrom under the shaft 44 100 and beneath the star wheel 47. This arm has at its ends spring control trips 51, 52. These normally extend upward, as shown in Fig. 10, and are in the path of the spokes of the wheel 47. Thus, as the carriage 7 105 approaches the ends of its horizontal movement in one direction, one trip, say the one 51, turns the wheel 47 and through the switch 43 cuts off the current to the motor 26 and stops the same. At the same time the 110 switch is actuated by said trip 51 to turn on the current to the motor 22 to start the same for lowering the carriage 7. After the carriage has been raised, the motor 22 is cut out and the one 26 turned on by the switch being actuated by the rod 48 and wheel 46, heretofore described. As the carriage 7 is 115 returned to its starting position by the motor 26, the trip 52 operates against the wheel 47 to cut out the motor 26 and turn 120 on the one 22.

By the construction described, the machine is automatic in its operation. A plurality of products is cast and discharged at regular intervals, the carriage being raised 125 and lowered and moved horizontally endwise for the purposes mentioned through the operation of a switch mechanism controlled and operated through the movement of the machine. This allows a greater production 130

per machine, and filling the molds in the manner stated gains substantially a perfect product.

While I have shown and described herein in detail a casting machine constructed in accordance with my invention, it is of course to be understood that the details of construction and arrangement of parts illustrated may be variously changed and modified without departing from the spirit and scope of my invention.

I claim as my invention:

1. A casting machine, comprising a crucible adapted to contain molten metal, a mold, and mechanical means acting to dip the mold into the crucible for filling, moving the filled mold into a discharging position, and returning the empty mold back to the crucible for refilling.
2. A casting machine, comprising a crucible adapted to contain molten metal, a mold, mechanical means acting to dip the mold into the crucible for filling, moving the filled mold into a discharging position, returning the empty mold back to the crucible for refilling, and mechanical means acting each time a filled mold is brought to discharging position to open the mold for discharging the same.
3. A casting machine, comprising a crucible adapted to contain molten metal, a mold, mechanical means acting to dip the mold into the crucible for filling, moving the filled mold into discharging position, returning the empty mold back to the crucible for refilling, and means in the path of movement of the mold to discharging position for opening the mold for discharging the same.
4. A casting machine, comprising a crucible adapted to contain molten metal, a plurality of molds, and mechanical means acting to dip said molds into the crucible for filling, moving the filled molds to discharging position, and returning the empty molds back to the crucible for refilling, said means acting to fill one mold while moving another to discharging position.
5. A casting machine, comprising a crucible adapted to contain molten metal, two molds maintained in spaced relation, and mechanical means for carrying the empty molds alternately from discharging positions at opposite sides of the crucible to the crucible for filling by dipping the molds into the crucible, and the filled molds back to the sides of the crucible for discharging, said means dipping one mold while moving the other to discharging position.
6. A casting machine, comprising a crucible adapted to contain molten metal, a vertically and horizontally movable mold, means acting each time the mold is brought over the crucible for moving the mold vertically into and out of the crucible for filling the mold with molten metal, means acting auto-

matically when the mold is filled and raised above the crucible for moving the mold horizontally to one side of the crucible for emptying the mold and returning the empty mold back over the crucible for refilling, and means acting each time the filled mold is brought to one side of the crucible for opening the mold and allowing the cast product to be discharged therefrom.

7. A casting machine, comprising a crucible adapted to contain molten metal, a vertically and horizontally movable mold having separable mold members, means acting each time the mold is brought over the crucible for moving the mold vertically into and out of the crucible for filling the mold with molten metal, means acting automatically when the mold is filled and raised above the crucible for moving the mold horizontally to one side of the crucible for emptying the mold and returning the empty mold back over the crucible for refilling, and means acting each time the filled mold is brought to one side of the crucible for opening the mold by separating the members thereof and allowing the cast product to be discharged therefrom.

8. A casting machine, comprising a crucible adapted to contain molten metal, a vertically and horizontally movable mold having separable mold members, means for moving said mold vertically when over the crucible into and out of the same for filling the mold with molten metal, and when at one side of the crucible moving the mold into and out of emptying position, means acting automatically for moving the mold horizontally into and out of said positions, and means in the path of downward movement of the mold at one side of the crucible for opening the mold by separating said mold members and allowing the cast product to be discharged therefrom.

9. A casting machine, comprising a crucible adapted to contain molten metal, a vertically and horizontally movable carriage above said crucible, two molds supported from said carriage in lateral spaced relation, means for moving the carriage horizontally when the molds are above the crucible for carrying the molds alternately from positions at opposite sides of the crucible to a position over the same, means for moving the carriage vertically for filling one mold by dipping the same into and out of the crucible and at the same time moving the other mold into and out of emptying position at one side of the crucible, and means for opening the molds as they descend at opposite sides of the crucible for discharging the cast products therefrom.

10. A casting machine, comprising a crucible adapted to contain molten metal, a vertically and horizontally movable carriage above said crucible, two molds supported

from said carriage in lateral spaced relation, power driven means for moving the carriage horizontally, when the molds are above the same, for carrying the molds 5 alternately from positions at opposite sides of the crucible to a position over the same, separate power driven means for moving the carriage vertically for filling one mold by dipping the same into and out of the 10 crucible and at the same time moving the other mold into and out of emptying position at one side of the crucible, means for opening the molds as they descend at opposite sides of the crucible for discharging 15 the cast products therefrom, and means operable through the movement of said carriage for controlling the action of said power driven means.

11. A casting machine, comprising a crucible adapted to contain molten metal, a vertically and horizontally movable carriage above said crucible, two molds supported from said carriage in lateral spaced relation, electrically actuated means for moving 20 the carriage horizontally for carrying the molds alternately from positions at opposite sides of the crucible to a position over the same, separate electrically actuated means for moving the carriage vertically for filling one mold by dipping the same into and out of the crucible and at the same 25 time moving the other mold into and out of emptying position at one side of the crucible, means for opening the molds as they descend at opposite sides of the crucible for discharging the cast products therefrom, and an electric switch mechanism in circuit with both of said electrically actuated means and operable through the movements of said 30 carriage for controlling the starting and stopping of the same.

12. A casting machine, comprising a base, a crucible thereon and adapted to contain molten metal, upright standards secured to 45 said base on opposite sides of said crucible, rails extending between said standards and slidably connected therewith, a carriage between and horizontally movable on said rails, two molds supported from said carriage in lateral spaced relation, means for moving said carriage horizontally over said rails for carrying the molds alternately from positions at opposite sides of the crucible to a position over the same, means for 50 moving the rails vertically for filling one mold by dipping the same into and out of the molten metal in the crucible and at the same time moving the other mold into and out of emptying position at one side of the crucible for discharging the cast products therefrom.

13. A casting machine, comprising a base, 55 a crucible thereon and adapted to contain

molten metal, upright standards secured to said base on opposite sides of said crucible, sleeves slidably mounted on said standards, rails secured to and extending between said sleeves, a carriage extending between and horizontally movable on said rails, two molds supported by said carriage in lateral spaced relation, each mold comprising a fixed mold member and a movable mold member, means for moving said carriage horizontally on said rails for carrying the molds alternately from positions at opposite sides of the crucible to a position above the same, means for moving the rails vertically for filling one mold by dipping the same into and out of the crucible and at the same time for emptying the other mold at one side of the crucible, and inclined rails on opposite sides of the crucible and in the path of downward movement of the molds for opening the same by separating the mold members as the molds descend at the sides of the crucible.

14. A casting machine, comprising a base, a crucible thereon and adapted to contain molten metal, upright standards secured to said base on opposite sides of said crucible, rails extending between said standards and having sliding connection therewith, a carriage between and slidably mounted on said rails, two molds supported from said carriage in lateral spaced relation, means including a yoke and crank shaft for moving said carriage horizontally on said rails for carrying the molds alternately from opposite sides of said crucible to a position above the same, cam means for moving the rails vertically for filling one mold by dipping the same into and out of the molten metal in the crucible and at the same time moving the other mold into and out of emptying position at one side of the crucible for discharging the cast product therefrom, and means operable through the movement of said carriage for controlling the actuation of said crank and cam means.

15. A casting machine, comprising a base, a crucible thereon and adapted to contain molten metal, upright standards secured to said base on opposite sides of said crucible, sleeves slidably mounted on said standards, rails secured to and extending between said sleeves, a carriage extending between and slidably mounted on said rails, two molds supported by said carriage in lateral spaced relation, each mold comprising a fixed mold member and a movable mold member, frames extending between said rails at the ends thereof and secured to said sleeves, a roller on each frame, a horizontal shaft below said crucible, cams on said shafts, one for each frame and engaging said rollers for moving said carriage vertically, a crank shaft, a yoke engaging the same and connected with said carriage for moving

the same horizontally, means for rotating said two shafts, rollers on the movable mold members, and inclined members in the path of downward movement of said rollers as 5 the molds descend for opening the molds and allowing discharge of cast products therefrom.

16. A casting machine, comprising a base, a crucible thereon and adapted to contain 10 molten metal, upright standards secured to said base on opposite sides of said crucible, sleeves slidably mounted on said standards, rails secured to and extending between said sleeves, a carriage between said rails and 15 slidably mounted thereon, two molds secured to said carriage and depending therefrom, each mold having fixed and movable mold members, electrically actuated means for moving the carriage vertically for filling 20 one mold by dipping the same into and out of said crucible and for moving the other mold into and out of emptying position at one side of the crucible, a separate electrically actuated means for moving 25 said carriage horizontally on said rails for moving said molds alternately from positions at opposite sides of said crucible to a position over the same, a shaft extending between and mounted on the standards at 30 one end of the machine, a rotary switch mechanism operated by said shaft, two rotary members fixed on said shaft, one operated in the vertical movement of said carriage and the other in the horizontal move-

ment thereof, and means carried by said carriage for operating said rotary members to effect the starting and stopping of said carriage operating means.

17. A mold, comprising fixed and hinged mold members having a cavity therebetween, 40 and spring pressed ejector pins carried by said mold members for ejecting the cast product from said cavity when the mold is opened upon separating the members thereof, the opposed ends of adjacent pins being in contact when the mold is closed and having notches to receive the cast product and engage the same.

18. A casting machine, comprising a crucible adapted to contain molten metal, a 50 mold, a carrier therefor, electrically actuated means acting on said carrier for dipping said mold into and out of the crucible for filling the mold, separate electrically actuated means acting on said carrier for 55 moving the filled mold to discharging position and returning the empty mold back to the crucible for refilling, means for opening the mold when at discharging position, and an electric switch mechanism in circuit 60 with both of said electrically actuated means and operable through the movement of said carrier for controlling the starting and stopping of the same.

In testimony that I claim the foregoing 65 as my invention, I affix my signature this 23 day of August, A. D. 1921.

ERWIN L. WILKE.
